UNITED STATES PATENT OFFICE.

CHARLES H. HODGKINS, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC SWITCH.

Application filed February 4, 1921. Serial No. 442,370.

To all whom it may concern:

Be it known that I, CHARLES H. HODGKINS, a subject of the King of Great Britain, and a resident of Pittsburgh, in the county of Allegheny and State of Pennsylvania, have invented a new and useful Improvement in Electric Switches, of which the following is a specification.

My invention relates to electric switches and particularly to those of the snap type.

One of the objects of my invention is to provide a switch of the character described wherein quickness and accuracy of movement are secured by the use of a minimum number of parts.

Another of the objects of my invention is to provide a switch-actuating mechanism of such construction as to insure against suspension of movement of the tensioned members when the line dividing the opposite angles of pressure is reached, in order to lessen the tendency of the contact members to spark and to thereby conserve their life and efficiency.

I accomplish the foregoing objects by means of two members pivoted eccentrically to each other, one of them having lost-motion engagement with a movable contact member and each supporting one of the ends of a tension spring in such manner that, when the actuating member is moved a distance sufficient to carry the spring across the center line of one of the pivots, the direction of tension on the other member, or striker arm, will be shifted, and, by reason of its lost-motion connection with the movable contact member, it will strike the movable contact member a hammer blow during its movement to the reverse position, under the action of the spring, and will carry the movable contact member to open or to closed position, as the case may be.

My invention is illustrated in the accompanying drawings as mounted in a switch box of any desired type.

Figure 1 is a front elevational view of the switch box, a portion of the cover being broken away to show the relation of the switch parts when in closed position;

Fig. 2 is a similar view showing the parts in open position, and

Fig. 3 is a side elevational view of the parts in open position.

The switch is illustrated as mounted on

a base 3 that is supported in a box 4 and includes a rocker arm 5 pivoted on the base 3, at 6, a striker arm 7, a movable contact member 9 and a stationary contact member 12. The movable contact member 9 is supported by a flexible arm 10 that is, in turn, secured to a bar 11. The bar 11 is pivotally supported at 6, independently of the rocker arm 5. The striker arm 7 is supported on the bar 11 by the pivot 8.

A spring 13, which is secured, at its opposite ends, to the members 5 and 7, respectively, is normally under tension. A handle 14 is provided for convenient actuation of the switch through engagement with the one or the other of the projections 15 and 16 of the rocker member 5. A spring 17 is provided for returning the handle to normal position after each actuation of the rocker member.

When the parts are in the position illustrated in Fig. 1, the spring 13 exerts a force tending to maintain the movable contact member 9 in firm engagement with the stationary member 12, by reason of the engagement of the lug 19 of the striker arm 7 with the arm 10 of the movable contact member. If the handle 14 be now moved, in a counter-clockwise direction, into engagement with the lug 16 to carry the spring 13 past the center line of the pivot 6, the angle of tension exerted on the member 5 is shifted, and the movement of such member is completed, independently of the handle 14, and the spring passes the center line of the pivot 8 also, thus shifting the direction of tension on the striker arm and causing it to snap, in a clockwise direction, to the position in which it is illustrated in Fig. 2.

During the travel of the striker arm to reverse position, its lug 20 will be brought into engagement with the arm 10 of the movable contact member, striking such arm a hammer blow and making a quick break of the engagement between the contact members 9 and 12 to open the circuit through the terminals 21 and 22. Stop members 25 and 26 are provided to limit the movement of the bar 11 and the lever arm 5.

An important feature of the invention resides in the provision of means for overcoming the tendency in snap switches of the ordinary type to arc when the spring

reaches the dividing line of the opposite angles of pressure. At that point, there is ordinarily no pressure exerted on the movable contact member, and arcing takes place, especially if the spring is at the neutral point.

By means of my device, the movable contact member is constantly under the tension of the spring 13 until after the spring 10 is carried past the center line of the pivot 6. When the spring has passed that point, the member 5 is free to be moved by the spring, independently of the handle 14. The spring, by reason of its tension, moves 15 past the center line of the pivot 8 and snaps the striker arm 7 to the position of Fig. 2. No matter at what point the actuating member 5 may be stopped, the tension of the spring on the movable contact member will 20 not be maintained in a neutral direction, and there will, consequently, be no "chattering" or relative vibration of the two contact members.

A reverse movement of the handle 14 will 25 bring it into engagement with the projection 15 of the rocker member 5 to cause a reversal of the movement just described. The stationary contact member 12 and a stud 27 serve as stop members when the movable 30 parts are in the position shown in Fig. 1.

If desired, the bar 11 may be dispensed with and the pivot 8 supported at a fixed point, and the arm 10 be either pivotally supported or it may be merely flexible, without any substantial variation in the method of operation.

It will be apparent that the invention might be applied to a variety of switches. For instance, it could be as conveniently employed in connection with multi-pole switches wherein the movable contact member, at each actuation thereof, would close a circuit through any one of a plurality of stationary contact devices, as desired.

Various other modifications will be readily apparent to those familiar with the art, and the scope of my invention is limited only as defined in the claims appended hereto.

50 I claim as my invention:—

1. An electric switch comprising, in combination, a movable contact member, a pivoted striker arm having lost-motion connection with the movable contact member, a 55 rocker arm pivoted eccentrically of the striker arm, a yielding member secured, at its opposite ends, to the rocker arm and the striker arm, respectively, and a lost motion means for moving the rocker arm to change 60 the direction of force exerted by the yielding member upon the striker arm.

2. An electric switch comprising, in combination, a movable contact member, a pivoted striker arm having lost-motion connection with the movable contact member,

a rocker arm pivoted eccentrically of the striker arm, a yielding member secured, at its opposite ends, to the rocker arm and the striker arm, respectively, and a lost motion means for moving the rocker arm to change 70 the direction of force exerted by the yielding member upon the striker arm and thereby cause an actuation of the movable contact member, such actuation including a blow due to the said lost-motion connection. 75

3. An electric switch comprising, in combination, a movable contact member, a striker arm having a lost-motion connection with the movable contact member, said lost-motion connection being adapted to be taken up before movement is imparted to the movable contact member, a tensioning device normally maintaining the striker arm in one of its extreme positions, and a member having lost motion connection with the striker arm for shifting the direction of tension exerted thereon to cause a snap movement thereof to reverse position.

4. An electric switch comprising, in combination, a movable contact member, a pivoted striker arm having a lost-motion connection with the movable contact member, a rocker arm pivoted eccentrically of the striker arm, a yielding member secured to the rocker arm and the striker arm, respectively, a handle for moving the rocker arm to shift the direction of force exerted on the striker arm by the yielding member, and a lost-motion connection between the handle and the rocker arm whereby the rocker arm is free to snap to its opposite position when the spring has been moved past the center line of the points of pivotal support. 95

5. An electric switch comprising, in combination, a movable contact member, a 105 striker arm having a lost-motion connection with the movable contact member, a tension member for normally holding the striker arm in one of its extreme positions, and a member having lost motion connection with the striker arm for shifting the tensioning device to cause the striker arm to move to its opposite position. 110

6. An electric switch comprising, in combination, a movable contact member, a pivoted striker arm having a lost-motion connection with the movable contact member, a pivoted arm, and a tensioning device having one of its ends connected to the striker arm and its other end connected to the said pivoted arm in such position that, upon movement of the pivoted arm, the line of force exerted by the tensioning device crosses the point of pivotal support for such arm before said line of force crosses the point of pivotal support of the striker arm pivot. 120

7. The combination, in an electric switch, of a movable contact member, a pivoted striker member therefor, a pivoted arm, a tensional connection between the arm and 125

the striker member, and means whereby, upon movement of the said arm, the line of tensional force is carried across the point of pivotal support for the arm before it is carried past the pivot of the striker member.

8. The combination, in an electric switch, of a movable contact member, a striker member, a movable arm, a tensioning device normally exerting tension on the striker member and the arm to maintain them in one of their extreme positions, means for shifting the direction of force exerted on the arm and the actuating member, and means whereby the line of force during such change of direction passes the point of support of the movable arm in advance of its passage across the supporting point of the striker member.

9. In combination, in an electric switch, a stationary contact member, a movable contact member, an operating lever, a tensional connection between the movable contact member and the operating lever for normally maintaining them in their extreme positions of movement, and means for maintaining the movable contact member in tensional engagement with the stationary contact member when the operating lever is free from the normal influence of the tension member.

30 10. In combination, in an electric switch, a movable contact member, an operating lever, a tensional member adapted to normally yieldingly maintain the said lever and the movable contact member in their extreme positions of movement, and means whereby the movable contact member is maintained under the normal influence of the tensional member during such time that the operating lever is not under said normal influence.

49 11. A switch comprising, in combination, a movable contact member and an operating lever both mounted on a fixed pivot, a striker arm pivoted on the movable contact member at a point removed from the said fixed pivot, a lost-motion connection between the outer end of the striker arm and the movable contact member, and means for exerting tension between the operating lever and the striker arm, the parts being so positioned that tension is directed against the pivotal support on the movable contact member during the time that the striker arm is moving from one point of lost-motion engagement to its other point of lost-motion engagement.

55 12. An electric switch comprising, in com-

bination, a pivotally supported contact member, an operating lever for said member, a striker arm, means for exerting tension between the operating lever and the movable contact member, and means whereby, during movement of the operating lever in one direction, the movable contact member is maintained under effective tension until the striker arm has been brought into operation to impart movement to the movable contact member.

13. An electric switch comprising, in combination, a movable contact member, a striker arm for imparting movement thereto, and common means for actuating the striker arm and for maintaining effective tension on the movable contact member during the time that the striker arm is being actuated.

20 14. A switch comprising a pair of relatively movable contact members and means for suddenly actuating one of said contact members into and out of engagement with the other contact member and for biasing said one contact member to its closed position until the instant of actuation therefrom, said means comprising a spring and a member pivotally connected to said one contact member.

25 15. A switch comprising a pair of relatively movable contact members and means for suddenly actuating one of said contact members into and out of engagement with the other contact member and for biasing said one contact member to its closed position until the instant of actuation therefrom, said means comprising a spring, a plurality of movable supporting members therefor, one of said supporting members having a pivotal connection and a lost-motion connection to said contact member.

30 16. An electric switch comprising, in combination, a pivotally supported contact member, an operating lever for said member, a striker arm, and means for exerting tension between the operating member and the movable contact member and for causing the striker arm to impart movement to the movable contact member in advance of the passage of the line of tensional force across the point of pivotal support for the movable contact member.

35 In testimony whereof, I have hereunto subscribed my name this 27th day of January, 1921.

CHARLES H. HODGKINS.
